UNITED STATES PATENT OFFICE.

SAMUEL S. FRETZ, OF PHILADELPHIA, PENNSYLVANIA.

GEAT FOR UMBRELLAS.

SPECIFICATION forming part of Letters Patent No. 694,957, dated March 11, 1902.

Application filed October 10, 1901. Serial No. 78,210. (No model.)

To all whom it may concern:

Be it known that I, SAMUEL S. FRETZ, a citizen of the United States, residing at Philadelphia, in the county of Philadelphia and 5 State of Pennsylvania, have invented new and useful Improvements in Umbrella-Frames, of which the following is a specification.

My invention appertains to the joint between the stretcher and the rib and belongs 10 to that class of joints in which the two opposite sides of the paragon rib are not rigidly secured to each other at the joint, but are allowed to spring toward and away from each other and support the ends of the lap, which 15 are folded in the inside of the stretcher, so that they will furnish a springing side bearing for the end of the stretcher, clamping it firmly enough to prevent any appreciable lost motion at the hinge-joint and so making 20 the umbrella very rigid, but at the same time allowing any sudden strain to be relieved by the springing of side walls. In my application No. 59,962 for a device of this class there was but two objections in certain 25 classes of umbrella-frames. In that application the pivot-pin penetrated one side wall of the rib and stopped either directly after passing through the end of the stretcher or after passing through the inside fold of the 30 lap. The first-mentioned construction had this practical difficulty, that a sufficient bearing for the pin was not provided in all cases, and the second-named, that the pin, being driven in and abutting directly upon the 35 highly-tempered steel of the rib, was liable at times to crack it. This was peculiarly objectionable because these cracks were not readily seen, and the rib often was made up into an umbrella before they were discovered.

40 In my present invention I carry the pin through both side walls of the rib, but not through the outer fold of the lap, and abut it against the inside of this outer fold.

Describing now in detail the best means 45 of which I am at present aware of embodying my invention, Figure 1 is a plan view of my invented device. Fig. 2 is a cross-section of the same on line $\alpha\alpha$ of Fig. 1.

The rib A is of the ordinary paragon construction, and the lap B is folded around the 50 belly of the rib, and the ends 33 thereof are folded inside of the side walls 55 of the rib to

form the side bearings for the end of the stretcher. Through the rib are pierced the holes C C, through which the pivot-pin D 55 passes. The pin D passes also through the end 7 of the stretcher E through its reinforce F. The end 7 of the stretcher E, and preferably also the reinforce F, are flattened to give a broader bearing-surface to fit against the side 60 bearings formed by the inside of the inwardly turned ends 33 of the lap B. The pin D passes through the outside fold of the lap folded around the rib, through the side wall of the rib, and buts against the inside of the 65 lap at the side of the rib opposite to that at which the pin was entered. The pin is then secured in place by giving it a blow or other suitable means being employed. The pin can either be secured fast to one side wall of 70 the rib and the stretcher turn upon it, or it can be secured to the stretcher and turn in bearings in the side wall of the rib, or be free to turn in either. It, however, should not be secured fast to both side walls of the rib, because by so doing the elastic springing of the 75 side walls of the rib is prevented.

Having now described my invention, what I claim, and desire to secure by Letters Patent, is—

80 The combination of a paragon rib, a lap surrounding the belly of said rib, and having the ends thereof folded inside the side walls of said rib, said rib being provided with holes in the side walls opposite each other and the 85 portion of the lap folded outside one of the side walls being provided with a hole registering with the hole in the side wall of the rib, and the outside fold of the lap adjacent to the opposite wall of the rib being integral, 90 a stretcher having a flattened end inserted between the ends of the lap and a pin penetrating the side walls of the rib and abutting against the inside wall of the said integral fold of the lap, and free to move inward and 95 outward in the side wall of the rib enveloped by the integral fold of the stretcher; substantially as described.

In testimony whereof I affix my signature in presence of two witnesses.

SAMUEL S. FRETZ.
